UNITED STATES PATENT OFFICE.

JAMES LELAND WOODSIDE, OF HAWARDEN, IOWA.

DESIGN FOR A CHIMNEY-CAP.

SPECIFICATION forming part of Design No. 28,237, dated February 1, 1898.

Application filed December 23, 1897. Serial No. 663,270. Term of patent 14 years.

To all whom it may concern:

Be it known that I, JAMES LELAND WOODSIDE, a citizen of the United States, residing at Hawarden, in the county of Sioux and State of Iowa, have invented a new and original Design for a Chimney-Cap, of which the following is a specification.

The leading feature of my design for a chimney-cap consists of a dome substantially square in plan view, a marginal flange extending at right angles to the dome at the base thereof, and an annular or cylindrical cap which rises from the top of the dome.

In the accompanying drawings, Figure 1 is a plan view of a chimney-cap showing my design. Fig. 2 is a side elevation. Fig. 3 is a vertical cross-sectional view.

As shown by the drawings, my design for a chimney-cap consists of the dome 5, which, viewed in plan, is substantially square, a marginal flange 6, projecting from the base of the dome, and an annular or cylindrical cap 7. The sides or walls of the dome are curved inwardly to join the flat top 8 of the dome, and from this flat dome-top rises the cylindrical cap. The diameter of the cap is less than the

width of the flat top 8, which presents a square outline when viewed in plan, and the annular cap lies within the marginal outline of the flat dome-top 8. The upper edge of the annular cap has an ornamental border consisting, preferably, of a series of notches forming a series of tongues; but this border is not material. The marginal flange 6 is square when viewed in plan, and it extends continuously around and outside of the marginal edges of the dome. Said marginal flange has a series of circular apertures which, in addition to ornamenting the flange, also serves a mechanical function in embedding the flange in mortar to provide for the attachment of the cap to a chimney.

What I claim is—

The design for a chimney-cap herein shown and described.

In testimony that I claim the foregoing as my own I have hereto affixed my signature in the presence of two witnesses.

JAMES LELAND WOODSIDE.
